UNITED STATES PATENT OFFICE

2,618,875

STEAM IRON

Joseph L. Vieceli, Cicero, Ill., assignor to Sunbeam Corporation, Chicago, Ill., a corporation of Illinois

Application May 27, 1948, Serial No. 29,542

3 Claims. (Cl. 38—77)

1

The present invention relates to steam irons and more particularly to that class of steam irons known as the flash boiler type of steam iron, which include a steam generator and a valve controlled water supply. Specifically, the present invention is an improvement on one feature of the arrangement disclosed and claimed in copending Jepson application, Serial No. 29,461 filed concurrently herewith and assigned to the same assignee as the present application.

In steam irons of the flash boiler type water is fed to a steam generating chamber, preferably defined in the sole plate of the steam iron, at a rate which allows the water to be flashed almost instantly into steam—hence the term flash boiler type of steam iron. The generated steam is distributed to the material being ironed by means of ports or the like which communicate with the steam generating chamber and open on the ironing surface of the sole plate. Irons of this type are usually provided with thermostatic means responsive to the temperature of the sole plate and selectively controllable to maintain the sole plate at a selectively controlled temperature depending upon the material to be ironed.

In irons of this type it is, of course, desirable that the valve for controlling the flow of water to the steam generator remain closed until the iron reaches its ironing temperature to insure instantaneous flashing of the water into steam. In steam irons heretofore employed difficulty has been encountered in obtaining sufficient flow of water to the steam generating chamber after the sole plate has heated up to ironing temperature, but before the water in the reservoir associated with the iron has been heated substantially. In the above mentioned copending Jepson application there has been disclosed an arrangement whereby in addition to the needle valve control for the flow of water from the reservoir to the steam generating chamber there is provided a by-pass or passageway which is valve controlled to insure the build-up of a small amount of pressure in the reservoir of the iron so that satisfactory flow of water to the steam generating chamber occurs as soon as the sole plate has been heated to ironing temperature. The present invention is particularly concerned with an improvement on the valve controlled by-pass for permitting such operation.

Accordingly, it is an object of the present invention to provide a new and improved steam iron.

It is another object of the present invention to provide a new and improved steam iron in which

2

a steady supply of steam is provided as soon as the sole plate is hot, without the requirement of waiting until steam is produced in the reservoir to force the water into the steam generating chamber.

It is a further object of the present invention to provide a combined needle valve control and bypass arrangement for properly controlling the water flow from the reservoir to the steam generating chamber of a steam iron.

Further objects and advantages of the present invention will become apparent as the following description proceeds, and the features of novelty which characterize the invention will be pointed out with particularity in the claims annexed to and forming a part of this specification.

For a better understanding of the present invention reference may be had to the accompanying drawing in which:

20 Fig. 1 is an elevational view partly in section of a steam iron embodying the present invention;

Fig. 2 is a sectional view taken on line 2—2 of Fig. 1 assuming that Fig. 1 shows the complete structure;

25 Fig. 3 is a partial sectional view taken on line 3—3 of Fig. 1 assuming again that Fig. 1 shows the complete structure; and

Fig. 4 is a sectional view taken on line 4—4 of Fig. 1, also assuming that Fig. 1 shows the complete structure.

30 Referring now to the drawing, there is shown an embodiment of the present invention in the form of a steam iron generally designated at 10 comprising an electrically heated sole plate 11.

35 The sole plate is heated by an electrical element 12 which preferably is of the sheathed type. Briefly, it comprises an electric resistance conductor mounted in an outer metallic sheath and supported in spaced relationship in reference to a sheath by an electrical insulated heat conducting mass formed of a suitable material such as a highly compressed magnesium oxide. The heating element 12 is preferably embedded in the sole plate 11 which latter is provided with an upright rib 13 in which the heating element 12 is received.

40 For the purpose of defining a steam generating chamber which is in close heat transfer relationship with the heating element 12 or at least with the rib 13 in which the heating element 12 is disposed, the front portion of the sole plate 11 is provided with a well or chamber generally designated at 14 and best shown in Figs. 1 and 4 of the drawing. This chamber 14 is defined within the closed end of the rib 13 which is of somewhat U-shaped configuration. The top of the steam

generating chamber 14 is defined by a cover plate 15 which is suitably related to the rib 13 to provide a sealed chamber 14.

Centrally disposed in the steam generating chamber 14 is a raised somewhat circular portion 16 forming an integral part of the sole plate 11 and having integrally formed therewith rearwardly extending legs or baffle members 16a and 16b so as to divide the steam generating chamber 14 into a series of passageways. The raised portion 16 is provided on its upper surface with a circular recess 17 exposing the upper end of a tapped bushing 18 which is integrally cast into the sole plate 11.

In view of the fact that the steam generating chamber 14 is closely confined within the closed end of the U shaped rib 13 which houses the heating element 12, water supplied to the recess 17 defined in the raised member 16 is adapted to be substantially instantly changed into steam and to pass through suitable notches 20 formed in the wall defining the recess 17 toward the rear portion of the steam generating chamber 14. This steam may pass around the ends (not shown) of the baffle members 16a and 16b into passageways 22a and 22b which join each other at the end of the steam generating chamber 14 adjacent the front of the steam iron 10 where there are provided a plurality of ports 23 which connect the steam generating chamber 14 with the ironing surface of the sole plate 11. To be sure that only steam and no water may pass through the ports 23 these ports open into the steam generating chamber 14 at the top surface of a raised V shaped member 24, also integrally formed with the sole plate 11, consequently, the ports opening on the ironing surface of the sole plate 11 are arranged in a sort of V shaped configuration. Preferably also the ends of the ports or steam passageways 23 at the surface of the sole plate 11 are of somewhat enlarged diameter as designated by the reference numeral 23a in Fig. 1 of the drawing.

The rear portion of the sole plate 11 is provided with a suitable well (not shown) for accommodating a suitable thermostatic control device for controlling the temperature of the sole plate 11. The particular arrangement of the thermostatic control device in the well of the sole plate 11 is fully disclosed in the above mentioned copending Jepson application.

In order that the steam generating chamber 14 may be provided with a source of water which is flashed into steam in the steam generating chamber 14, there is provided a water reservoir generally designated at 25 which has an external configuration closely approaching the size and shape of conventional irons. In other words, the reservoir 25 does not have such an exterior dimension as to make the steam iron appear unusually large or bulky as is the case with many steam irons now available on the market. Preferably the reservoir 25 is formed from a pair of sheet metal stampings comprising a bottom member 25a and a top member 25b which are suitably joined to form a sealed container. For the purpose of permitting control connections to be made between the well in the sole plate referred to above and portions of the steam iron disposed above the reservoir 25, a suitable passageway 26 is provided through the reservoir 25 which passageway is defined by a somewhat tubular member 27, the upper and lower ends of which are sealed to the top and between members 25b and 25a respectively to prevent any danger of leak-

age of water from the reservoir 25. In addition to the passageway 26, the reservoir 25 is provided with a pair of openings designated as 28 and 29 respectively. The opening 28 is defined in the wall 25b near the front of the iron and is adapted to receive a cylindrical steam dome 30, the lower end of which is suitably sealed to the wall 25b so as effectively to provide a steam dome extending a substantial distance above the top of the reservoir 25. The opening 29 on the other hand is disposed in alignment with a tapped opening defined in the bushing 18. This opening 29 is furthermore formed at the bottom of a somewhat cone shaped indentation 31 in the bottom wall 25a of the water reservoir 25, as is clearly shown in Figs. 1 and 3 of the drawing, thereby providing a good seal between the tank 25 and a valve body 32 of a needle valve and furthermore aiding in aligning the tank 25 and the sole plate 11 during assembly thereof. The needle valve comprising the valve body 32 and a needle valve member 33 is provided to control the flow of water from the reservoir 25 to the steam generating chamber 14. The needle valve body 32 comprises a conical surface for engagement with the indentation 31 and further includes a threaded extension adapted to engage with the tapped opening in the bushing 18. Effectively, therefore, the valve body 32 performs three functions; (1) it includes the valve seat for the needle valve member 33 to be described hereinafter, (2) it provides suitable means for fastening the tank or reservoir 25 to the sole plate 11, and (3) it provides means for holding the cover plate 15 of the steam generating chamber 14 in position. The external surface of the needle valve body 32 extending into the reservoir 25 is of circular configuration as best shown in Fig. 3 of the drawings so as to be readily insertable through an opening in the top of the steam dome 30. Preferably the valve body 31 is provided with a screw driver engaging slot 34 whereby a screw driver inserted through an opening in the top of the steam dome may be employed when assembling the reservoir 25 on the sole plate 11 which is done in a simple manner after the tank 25 and the steam dome 30 have been completely assembled. The valve body 32 is preferably provided with a plurality of substantially horizontally disposed passageways 36 through which the water from the reservoir 25 may enter the needle valve and flow along the surface of the needle valve member 33. The valve body 31 further includes a passageway 37 which permits water flowing through the needle valve to pass into the recess 17, in the steam generating chamber 14.

In order manually to control in a selective manner the flow of water from the reservoir 25 to the steam generating chamber 14 by means of the needle valve comprising the valve body 32 and the needle valve member 33, the latter comprises an elongated member extending upwardly along the axis of the steam dome 30. The lower end of this member 33 is tapered in the form of a conventional needle valve and is threadededly engaged with the valve body 32 so as effectively to provide a needle valve control with the flow of water being along the external surface thereof. It will be understood that rotation of the needle valve member 33 in one direction will completely shut off the flow of water from the reservoir 25 to the steam generating chamber 14 in a conventional well understood manner. On the other hand rotation of the needle valve member 33 in the other direction will permit variable

amounts of water to flow into the steam generating chamber 14 depending upon the amount of rotation.

In the above mentioned copending Jepson application there is disclosed a valve controlled passageway interconnecting the steam dome 30 with the steam generating chamber 14. This arrangement insures the satisfactory flow of water to the steam generating chamber 14 as soon as the sole plate is hot enough for ironing purposes. The reason for this is that a certain amount of air is always left in the water reservoir 25 and as soon as the initial heating of the sole plate 11 occurs, there results an expansion of this air and the creation of some pressure within the reservoir 25. Preferably the valve controlled passageway permits a pressure of approximately 1½ pounds per square inch to be obtained in the steam dome 30 before opening of the by-pass occurs. This arrangement is broadly disclosed and claimed in the copending Jepson application referred to above.

In accordance with the present invention, a separate by-pass passageway is dispensed with and instead the needle valve member 33 is formed from a suitable tube so as to include a central passageway 40 along the longitudinal axis thereof, thereby interconnecting the upper end of the steam dome 30 and the steam generating chamber 14 independently of the passageway afforded along the exterior of the needle valve member 33 within the valve body 32. As illustrated the upper end of the needle valve member 33 is telescopically related with a fitting 41 comprising a portion which extends out of the upper end of the steam dome 30. The fitting 41 is suitably fastened to the upper end of the member 33 and includes a lower tubular portion 41a connected by passageways 42 with the space within the steam dome 30. To prevent the escape of steam from the upper end of the steam dome 30 it is closed by a suitable plug 43 threadedly engaging the steam dome and including a suitable packing around the portion of the fitting 41 which extends through the plug 43. Preferably a steam control button 44 formed of molded insulating material or the like is attached to the fitting 41 which extends out of the steam dome 33 by means of a screw 45 inserted through the top of the button 44 and threadedly engaging a tapped opening in the top of the fitting 41.

In order to limit the open and closed positions of the needle valve member 33 the control button 44 is preferably provided with a depending lug 44a which engages a stop 30a illustrated as comprising an integral extension from the upper end of the steam dome 30. The lug 44a engages opposite sides of the stop 30a in the extreme open and closed positions thereof.

In accordance with the teachings of the above mentioned Jepson application the passageway interconnecting the steam dome and the steam generating chamber is provided with a pressure operated control valve. As illustrated in the drawing there is provided in the passageway 40 a spring biased ball valve 47 normally biased by means of a coiled spring 48 against a seat defined in the fitting 41, so as effectively to isolate the passageway 40 from the passageways 42. Preferably the ball valve 47 is adjusted so as to require a pressure of approximately 1½ pounds per square inch within the steam dome 30 to open the same. This arrangement assures satisfactory water flow into the steam generating

chamber 14 as soon as the sole plate 11 is hot enough for ironing purposes.

It will be apparent from the above description that with the present invention the needle valve member 33 serves a dual function being both a needle valve member and a by-pass or passageway for interconnecting the steam dome 30 with the steam generating chamber 14.

In accordance with the arrangement described in the above mentioned Jepson application, the steam iron 10 includes a handle 50 suitably fastened to the remainder of the steam iron and a spacer plate 51 interposed between the handle 50 and the reservoir 25, which plate has an opening 51a for the steam dome 30. The handle 50 further includes a cored chamber 52 defined in one end thereof for receiving the steam dome 30 whereupon the steam control button 44 extends slightly above the top of the handle 50 for ready finger manipulation thereof. Preferably the steam control button 44 is provided with a suitable extension cooperative with an index point provided on the handle 50 so that the operator may know at a glance in what position the steam valve is.

The cored chamber 52 also houses the means for obtaining selective control of the temperature of the sole plate 11 and as is disclosed in the above mentioned Jepson application the steam dome 30 is provided with an upper portion 30b of reduced cross section so as to define an annular shoulder 54. Concentrically disposed about the portion 30b of the steam dome and resting on the shoulder 54 is a rotatable cam member 55 which is manually rotated by means of a temperature control button 56 concentrically arranged with the steam control button 44. A suitable cam follower 57 engages the rotatable cam 55 which cam follower is constrained to move in only a vertical direction. The button 56 is provided with a depending lug 58 which cooperates with a stop 59 formed as an integral part of the handle 50 within the cored chamber 52 to limit the extreme portions of the cam 55. The cam follower 57 is connected by means of a tension spring 60, with suitable thermostatic control means, not shown, disposed within a well defined in the sole plate 11, the interconnection extending through the passageway 26 mentioned above. The details of the selective temperature control means described form no part of the present invention but are disclosed and claimed in the above mentioned copending Jepson application.

In view of the detailed description included above the operation of the steam iron of the present invention will be apparent to those skilled in the art. By virtue of the passageway 40 within the needle valve 33 a small pressure not exceeding about 1½ pounds per square inch is required within the reservoir 25 to insure the flow of water between the reservoir 25 and the steam generating chamber 14. Furthermore this pressure is available as soon as the sole plate 11 is hot enough to begin the ironing operation and it is not necessary to wait for steam to form within the reservoir 25 before proper functioning of the steam iron 10 is obtained. When the needle valve member 40 serves in its dual capacity in accordance with the present invention a very simple and compact arrangement is provided which is sturdy and fool proof in operation.

While there has been shown and described a particular embodiment of the present invention,

it will be apparent to those skilled in the art that various modifications and changes can be made without departing from the present invention in its broader aspects, and it is therefore aimed in the appended claims to cover all such changes and modifications as fall within the true spirit and scope of the present invention.

What is claimed as new and desired to be secured by Letters Patent of the United States is:

1. A steam iron comprising a closed water reservoir, a steam generating chamber, a needle valve controlling the flow of water by gravity from said reservoir to said steam generating chamber, said valve comprising a valve seat and an elongated member with the valve means for controlling the flow of water being disposed at the end of said member cooperating with said seat, the water flow occurring along the outer surface of said one end, said member extending above said water reservoir to provide a manipulating member for said needle valve, means defining a passageway through said member interconnecting the upper portion of said water reservoir with said steam generating chamber, and valve means in said passageway for maintaining a pressure differential between said water reservoir and said steam generating chamber.

2. A steam iron comprising a closed water reservoir, a steam generating chamber, a needle valve controlling the flow of water by gravity from said reservoir to said steam generating chamber, said needle valve comprising a valve seat and an elongated member with the valve means for controlling the flow of water being disposed at the end of said member cooperating with said valve seat, the water flow occurring along the outer surface of said one end, said member extending above said water reservoir to provide a manipulating member for said needle valve, means defining a passageway through said member interconnecting the upper portion of said water reservoir with said steam generating

chamber, and a valve member biased to the closed position disposed in said passageway for maintaining a pressure differential between said water reservoir and said steam generating chamber.

3. A steam iron comprising a closed water reservoir, a steam dome comprising a tubular member connected to and extending above said water reservoir, a steam generating chamber, a needle valve controlling the flow of water by gravity from said reservoir to said steam generating chamber, said needle valve comprising a valve seat and a manually movable valve member in the form of a tube extending through said water reservoir and into said steam dome, one end of said valve member cooperating with said valve seat means defining an opening in said tube interconnecting the passageway therein with said steam dome to provide an interconnection between said steam dome and said steam generating chamber, and a valve means in said passageway to prevent said intercommunication until a predetermined pressure is produced in said reservoir.
